UNITED STATES PATENT OFFICE.

WILLIAM S. RICHARDSON, OF BOSTON, MASSACHUSETTS, ASSIGNOR TO THE
BALL AND SOCKET FASTENER COMPANY, OF NASHUA, NEW HAMPSHIRE.

GLOVE-FASTENER.

SPECIFICATION forming part of Letters Patent No. 399,161, dated March 5, 1889.

Application filed May 26, 1888. Serial No. 275,228. (No model.)

To all whom it may concern:

Be it known that I, WILLIAM S. RICHARDSON, of Boston, in the county of Suffolk and State of Massachusetts, a citizen of the United States, have invented a new and useful Improvement in Fasteners for Gloves and other Articles, of which the following is a full, clear, and exact description, reference being had to the accompanying drawings, forming a part of 10 this specification, in explaining its nature.

The invention relates to a fastener comprising, first, a member or section consisting of a ball fastened or secured to the under side of the material by means of a cap applied to the 15 other or upper surface of the material, and, second, a socket or ball-receiving section or member of peculiar construction.

Referring to the drawings, Figures 1 and 2 are detail views of the cap, Figs. 3 and 4 of the washer, and Fig. 5 of a solid ball with a shank. In Fig. 6 these parts are assembled together to form the ball member of the fastening. Figs. 7 to 13, inclusive, relate to the 20 same member of the fastening, representing a slight modification in construction. Figs. 25 14 to 18, inclusive, also refer to the same member of the fastening, representing still another modification in construction. Figs. 19 to 22, inclusive, show the ball-holding member of the fastening; and Fig. 23, the two members of the fastening together.

The ball member of the fastening comprises a ball, *a*, disposed upon the under surface of the material of the glove or other article with 35 which it is used, and a cap, *a'*, placed upon the upper surface of said material, the ball, material, and cap being united in a manner to bring the material and ball within, to a greater or less extent, the cavity of the cap.

In Fig. 5 I have represented the ball as 40 solid and having a shank, *a²*. A washer, *a³*, which encircles the shank, bears against the ball and serves to secure or hold the material against the under surface of the cap by the 45 upsetting of the upper end of the shank upon the cap.

In Fig. 18 I have shown a hollow ball which is made with a large flange, the flange taking 50 the place of the washer *a³*, and the hollow ball is secured to the cap by means of an eyelet or

fastening passing through a hole in the cap and upset or enlarged in the cavity of the ball.

In Fig. 13 I have represented a hollow ball with a large flange, which takes the place of the said washer *a³*, and I have represented it 55 as united to the material and cap by flattening the flange of the ball within the cavity of the cap, the lower edge of the cap having been drawn in.

B represents the member or section for receiving and holding the ball. It is made from a flat blank of the general shape represented in Fig. 19, which is provided with the holes *b b'*. The metal about the hole *b'* is struck or drawn up to form raised jaws *b²* about the 60 opening and leaving a flat flange, *b³*, about the base of the jaws. There is also formed the slit or slits *b¹*, which preferably extend from the opening *b'* to the flange. The hole *b* in the ear *b⁵* serves to receive the eyelet *b⁶* or 65 other fastening by which the section is secured to the material. It will be seen that there is thus provided a socket member comprising a flat base and jaws extending upward from the said base, which approach each other 70 at the top and form an opening for the reception of the ball, there being, of course, a larger cavity or space below the opening for the reception of the ball, the jaws being opened slightly to permit the passage of the ball and 75 then closing thereon by their spring or yielding action. The shape of the jaws is such as to extend upward about the ball and into the cavity of the cap, so that the draft of the fastening is practically upon a line with the material.

I would say that in the use of the terms "ball" and "socket" I do not mean to be understood that the ball member shall of necessity be spherical, or of a shape approaching a 80 sphere, for the member termed the "ball member" may have any other desired shape, and the socket member would be made to conform.

Having thus fully described my invention, I claim and desire to secure by Letters Patent 95 of the United States—

1. The ball member of a fastening, comprising the ball *a*, applied to one surface of the material upon which it is used, the cap *a'*, applied upon the opposite surface of said mate- 100

rial and having a cavity to receive the material and ball, and a washer or flange between the ball and material, the said ball being secured to the cap with the material to bring the principal part of its body within the edge of the material determined by the edge of the cap, substantially as described.

2. A socket member of a fastening, comprising a flat plate having at one end an ear, b^5 , affording means by which the member of the fastening is secured to the material, and at the other end the continuous flange b^3 , and the yielding or spring jaws b^2 , rising from the inner edge thereof and having an opening to receive the ball member of the fastening, substantially as described.

3. The combination, in a fastening for gloves and other articles, of the flat plate b^3 , the jaws b^2 , extending upward therefrom, and the slit

or slits b^4 , and an extension, b^5 , of the plate b^3 , for receiving a fastening for securing the member to the material with the ball, post, or stud member, substantially as described.

4. The combination, in a fastening for gloves and other articles, of a ball member comprising a ball, a , secured within a cavity formed in one surface of the material, and a cap located upon the other surface of the material, and a washer, the ball and washer being secured to the cap, and the washer and cap determining said cavity in the material, with a socket member having upwardly-extending yielding jaws b^2 , provided with an opening to receive the ball, substantially as described.

WILLIAM S. RICHARDSON.
